UNITED STATES PATENT OFFICE.

TOKICHI KATO, OF TACOMA, WASHINGTON.

WINDOW-CLEANER.

1,295,516.

Specification of Letters Patent. Patented Feb. 25, 1919.

Application filed June 24, 1918. Serial No. 241,496.

To all whom it may concern:

Be it known that I, TOKICHI KATO, a subject of the Emperor of Japan, residing at Tacoma, in the county of Pierce and State 5 of Washington, have invented certain new and useful Improvements in Window-Cleaners, of which the following is a specification.

This invention relates to window cleaning devices and is designed more especially for 10 cleaning the front window glass of a locomotive or street car to enable the engineer or motor man to clearly see the track in advance of the car.

The invention consists in the novel construction, adaptation and combination of devices as will be hereinafter described and claimed.

In the accompanying drawings,—

Figure 1 is a perspective view of a window 20 equipped with a cleaner embodying my invention, said view being taken from the rear side. Fig. 2 an elevational view of the same from the rear or inside. Figs. 3 and 4 are sectional views through 3—3 and 4—4 of 25 Fig. 1.

Referring to said drawings, the numeral 5 designates a pane of window glass of a sash 6 provided in a frame having side and head casing members 7 and 8. 9 represent upper 30 right pipes positioned in front of the window, and at opposite sides of the sash. Said pipes have their upper and lower ends socketed in cup elements 10 of brackets 11 which are rigidly secured to the casing members 35 7. Movable vertically in said pipes are cylindrical blocks such as 12, which are urged upwardly in the respective pipes by means of helical springs 13. Formed integral with, or rigidly secured to, each of said blocks is 40 an arm 14 extending through slots, as 15, of the pipes and also through slots 16 provided in the casing members 7.

Secured to the ends of said arms and inside 45 of the car is a horizontal handle bar 17. Outside of the car said arms are provided with branches 18 to which are secured the ends of a horizontal rod 19 to which is pivotally connected by means of bearings 20 a horizontally disposed blade 21 having connected 50 thereto a strip 22, of rubber, felt, or other material, suitable for cleaning the window pane 5.

Springs 23 coiled about the rod 19 serve 55 to yieldingly hold the strip 22 in juxtaposition with the outer or front surface of said pane. 24 represent deflectors secured to the

window sash adjacent to its top and are each provided with a resilient tongue 25 disposed in inclined relations with the plane of the window pane so as to engage studs 26 60 protruding from the ends of the blade 21 to swerve the latter with the strip 22 outwardly when the blade approaches the upper end of its travel. When the studs 26 ascend above the tongues 25, the springs 23 assert 65 themselves to return the strip 22 into contact with the window pane.

28 represents a hood secured to the casing member 8 and serves as a receptacle in which said blade and strip are housed and protected when unemployed.

For use the operator pulls down on the handle-bar 17 thereby lowering the blade 21 to cause the strip 22 to wipe downwardly any moisture or dirt which may have collected on the outside of the window pane. In thus pulling the cleaning devices downwardly the springs 13 are contracted so that upon the operator releasing the handle bar the power of the springs will act to elevate 80 said devices to its idle position above the window pane. In such upward movement of the cleaning devices, the tongues 25 cooperate with studs 26 to ward the strip from the glass for the purpose of passing over 85 any accumulation of dirt or moisture which may have been carried up with the strip, such dirt or moisture being carried in the next downward movement of the strip.

The invention is of simple and inexpensive 90 construction and is efficient in operation.

What I claim, is—

1. The combination in a window cleaning device, of a vertically movable rod, a cleaning strip pivotally connected to said rod, a 95 spring tending to retain said device in operative relation with the outside of the window pane, springs connected with both ends of said rod for yieldingly retaining said strip in its uppermost position, arms operatively 100 connected to the ends of said rod and extending through slots provided in the casing members, and a handle bar connected to said arms for effecting the downward movements of the strip from the inside of the 105 window.

2. The combination in a window cleaning device, of a horizontal rod at the outside of the window, a cleaning strip carried by said rod, and engaging the outside of the window 110 pane, slotted pipes secured to the window frame at opposite sides of the sash thereof,

- blocks provided in the respective pipes, arms extending from said blocks through the respective pipe slots and through slots provided in the casing member to the inside of 5 the window, said arms being provided with branches to which the aforesaid rod is secured, springs provided in the pipes and acting through the medium of said blocks to yieldingly retain the cleaning strip at its 10 uppermost position, and a handle bar connected to said arms for effecting the downward movements of the cleaning strip in opposition to said springs.
3. In an apparatus of the character described, 15 the combination in a window clean-

ing device, of a vertically movable window-pane cleaning strip, springs serving to press said device against the outside of said pane, and means to effect the vertical movements of the cleaner, of means to cause said strip 20 to be moved away from the pane during its upward travel when said strip is in proximity to its uppermost position.

Signed at Seattle, Washington, this 8th day of June, 1918.

TOKICHI KATO.
